United States Patent Office.

FERDINAND HAASE AND WILLIAM ROST, OF PROVISO, ILLINOIS.

Letters Patent No. 72,483, dated December 24, 1867.

IMPROVED SKATE.

The Schedule referred to in these Letters Patent and making part of the same.

TO ALL WHOM IT MAY CONCERN:

Be it known that we, FERDINAND HAASE and WILLIAM ROST, both of the town of Proviso, in the county of Cook, and State of Illinois, have invented a new and improved "Adjustable Skate-Frame;" and we do hereby declare that the following is a full and exact description thereof, reference being had to the accompanying drawings, and to the letters of reference marked thereon—

Figure 1 representing the side view, and

Figure 2 the top view of the frame.

Figure 3, a section of one of the projections, B, and

Figure 4 a tool, N.

The nature of our invention consists in so arranging the skate-frame that by means of adjustable plates the frame may be adjusted for feet of different sizes, and be used without straps.

To enable others skilled in the art to make and use our invention, we will proceed to describe its construction and operation.

The frame A is made of malleable iron, having projections B B underneath, with slots *a a*, to put in the runner and holes *b b* for the rivets to secure the same. There are two slots, *c c*, cut across the frame A in its front part, and a slot, D, cut longitudinally in its hind part. Two plates, E E, whose outward sides are bent upwards in a groove-like manner, are attached to the frame by means of set-screws, F F, and by means of slots *c c* may be adjusted for a narrow or a wide foot. There are two more adjustable plates, G and H, to adjust the frame to the length of the foot, and to attach the same to the boot-heel. The plate G has prongs, *g g*, projecting backward to enter the front part of the heel, and a steel spring, *g'*, to slide along as far as is needed, and to catch into the rack I cut in the skate-frame. The plate H has prongs, *h h*, to enter into the back part of the heel, and the loop K, with a screw-thread cut inside, through which passes an endless screw, S, supported by two of the projections B B, and having a square head, *t*. A tool, N, combining a screw-driver, *n*, and a wrench, *n'*, to work the set-screws F F, and the head of the endless screw S, is used to adjust the frame.

The operation consists in the following: The front plates E E, being adjusted to the width of the foot, the plate G is shifted along the rack I accordingly, and the plate H moved more or less to suit the length of the foot. Then the sole of the boot is driven tight into the grooves of the plates E E, the prongs of the plate G are forced into the front side of the heel, and the prongs of the plate H, by means of the wrench *n'*, operated on the head *t* of the screw S, are driven into the back part of the heel, and the skate is attached.

We propose to make three different frames, each capable of being adjusted to four different sizes of feet.

The advantages of our "adjustable skate-frame" consist in this, that the same skates may be used conveniently by persons of different sizes and age, and that it does not require any straps, and therefore is more comfortable for the foot.

What we claim as our invention, and desire to secure by Letters Patent, is—

A skate-frame, provided with the laterally-adjustable toe-clamps E, the adjustable sliding-clip G, made to embrace the shank I, and being held in place by the spring *g'*, engaging in the notches in shank I, and the heel-clip H, operated by the screw S, all arranged to operate substantially as shown and described.

FERDINAND HAASE,
WILLIAM ROST.
